BOTTLE CLOSURE

William A. Conway, Jr., Shamokin, Pa.

Application November 8, 1938, Serial No. 239,577

2 Claims. (Cl. 215—38)

This invention relates to closures for milk bottles and belongs to that type of closure known as hoods which include a skirt extending over the pouring lip and over a portion of the bottle neck to prevent contamination thereof by reason of exposure of these parts.

The use of protective hoods for milk bottles has been general in recent years. The hoods commonly in use today usually comprise constructions with which the ordinary disc stopper is used. Such stoppers are sometimes applied under the hood structure, although some arrangements have been in use which employ stopper discs slightly smaller than those commonly used and which are adapted to be pressed into the mouth of the bottle over the hood structure.

It has, furthermore, been customary heretofore to coat bottle hoods with a material rendered plastic by the application of heat. Thus, hood applying operations usually involve the application of heat to the hood enclosing the bottle neck to cause such hood to conform to the contour of the bottle and to maintain its contact with the external surface of such bottle after having been applied.

It is an object of this invention to provide a hood for the protection of the neck and pouring lip of a milk bottle which utilizes a pressure sensitive, self-sealing adhesive; a hood which may be applied to the mouth and neck of a bottle without the application of heat; and one which may be removed from and applied to the bottle neck repeatedly without losing its ability to conform to the contour of the bottle.

It is a further object of this invention to provide, if desired, a bottle hood so formed as to constitute a complete and effective seal for the mouth of the bottle without the aid of the stopper discs usually employed.

These and other objects and advantages of the invention will be made clear in the following description which is made with reference to the drawing forming a part thereof. In the drawing, like reference numerals indicate like parts, and:

Figure 1 represents the mouth and neck of a milk bottle having applied thereto the closure hood constituting the subject matter of this invention;

Figure 2 is a top plan view of the hood;

Figure 3 shows the blank from which the hood is formed and has indicated thereon the lines along which the blank is folded;

Figure 4 is a vertical sectional view taken on 55

line 4—4 of Figure 2, and shows a hood prior to its application to a bottle; and

Figure 5 is a sectional view taken on line 5—5 of Figure 2.

5 The hood shown as an example of an embodiment of the invention, is composed of a single circular blank of more or less flexible sheet material 10. This blank is suitably creased to permit the pleating of a major portion thereof in suitable capping machines during the application thereof to the mouth and neck of a milk bottle.

As shown in the drawing, the blank 10 is creased along more or less radial lines 12 which extend outwardly to the peripheral edge of the blank. The crease lines 12 define relatively wide panels 14 and panels 16 which are substantially half the width of the panels 14. The panels 16 adjacent alternate panels 14 are adapted to be folded under these adjacent panels so as to form 15 a pleat of the box type, best shown in Figure 5, wherein two contacting sets of such pleats are illustrated. Such in-folding of a portion of the material of which the hood is constructed, permits the same to be fitted snugly against the pouring lip and neck of a bottle.

20 In order to eliminate the use of the disc-like caps which are commonly employed as milk bottle closures, there is provided in this hood a relatively rigid self-sustaining cap portion 18. Several ways may be found to render the cap portion 18 self-sustaining. For example, the cap portion 18 or just a portion thereof, such as the annular portion, may be impregnated with a solution effective to render such impregnated portion rigid. The preferred manner herein shown involves the provision of a plurality of folded portions of the hood which define an annulus adapted to fit tightly into the mouth of a bottle and rest on the cap shoulder commonly provided in 25 such bottles.

More specifically, with reference to Figures 4 and 5, it will be noted that the pleated skirt 20 is adapted to extend upwardly over the neck of a bottle and inwardly over the pouring lip thereof. An annular portion 22 of the skirt is folded back upon itself to form several thicknesses of material at the region of the hood which enters the mouth of the bottle. By virtue of the folds in the skirt portion 20, the annulus 24 which is 30 formed by the overlapping sections 20 and 22 and the plain top portion 18, has therein seven thicknesses of material. When these plies are compressed they form a rigid self-sustaining structure which is capable of performing the sealing function of the ordinary disc type bottle cap.

It has been found advantageous to coat the inner surface of the hood with a self-sealing adhesive which has an affinity for itself at normal temperatures. Heretofore, such hoods have been coated or impregnated with substances which become plastic at elevated temperatures, and it has been an object of this invention to eliminate the use of heat in applying the hoods. The invention furthermore contemplates the use of an adhesive substance which is impervious to moisture and which has little or no affinity for glass.

According to this invention the preferred coating substance is a solution of latex in aqua ammonia. Such coating solution, in addition to the above-noted properties, has the further advantage of being unaffected by constituents of the milk. The aqua ammonia used in the solution is of sufficient strength to render the latex and the surface to which it is applied completely sterile.

In the use of a hood coated with an adhesive of this character, the same may be removed from the bottle a great number of times without tearing the material of which the hood is constructed, and without materially affecting the adhesive properties of the coating, and a hood so coated may be reapplied to the bottle simply by pressing the pleated folds about the neck thereof.

Should it be found desirable to render the hood

even more impervious to moisture the same may be coated externally with varnish, lacquer, or wax, as the circumstances may require.

The broad substance of the invention having been illustrated in connection with a specific embodiment, the practice thereof shall not be limited other than by the limitations which may be imposed thereon in the subjoined claims.

I claim:

10. A bottle hood formed of a single flexible sheet, comprising a pleated skirt portion formed of pleated sections folded upon themselves to conform to the contour of a bottle neck, and an integral self-sustaining disc portion formed at 15 its periphery of several compressed thicknesses of said pleated sheet adapted to enter and contact the mouth of a bottle in sealing engagement.

20. A bottle hood formed of a single flexible sheet, comprising a pleated skirt portion formed of pleated sections folded upon themselves to conform to the contour of a bottle neck, and an integral disc formed with a self-sustaining annulus formed by folding and compressing a portion of 25 said pleated skirt upon itself, said annulus constituting an abutment adapted to enter and contact the mouth of a bottle in sealing engagement.

WILLIAM A. CONWAY, JR.
